UNITED STATES PATENT OFFICE.

WALTER SCHÜRMANN, OF DUSSELDORF, GERMANY.

SPEED-INDICATOR.

1,073,443.

Specification of Letters Patent. Patented Sept. 16, 1913.

Application filed July 5, 1912. Serial No. 707,751.

To all whom it may concern:

Be it known that I, WALTER SCHÜRMANN, a citizen of the Empire of Germany, residing at Dusseldorf, in the Empire of Germany, have invented a new and useful Speed-Indicator, of which the following is a specification.

My invention relates to improvements in speed-indicators, in which the motion of a driven part is transmitted to an indicator by means of a medium, for instance air, enclosed in a vessel.

The chief improvement consists in that the driven part is a hollow cylindrical drum provided with radial ribs on the inside of the bottom, the side wall and the cover for taking along with them the medium, and in that the indicator is by its shaft connected with a fly concentric with the drum and adapted to pass with its wings between the radial ribs of the drum during the rotation of the latter for producing a friction of the medium which friction tends to turn the fly in the same direction as the drum. A spiral spring is connected at the inner end with the shaft of the fly and of the indicator and at the outer end with the frame and serves for counteracting the friction of the medium.

Another improvement consists in the novel construction of the fly, whereby its manufacture is facilitated. The hollow drum is further connected by a worm gearing with an operating shaft, which serves for operating the parallel main shafts of two counters.

A further improvement consists in a novel transmission from the operating shaft to the said two main shafts by means of a longitudinally guided reciprocating slide with two opposite pairs of spring-pressed pawls engaging from opposite sides in two ratchet wheels on the two main shafts.

A further improvement consists in forming the radial ribs in the hollow drum from a single piece of sheet metal by cutting and bending, the single piece having the shape of an annular disk with radial arms to be fastened on the bottom of the drum and of U-shaped wings at right angles to the arms. Thereby the manufacture of the hollow drum with the radial ribs is greatly facilitated and cheapened.

A further improvement consists in a plate made from a single piece of sheet metal by cutting and bending, which plate is adapted

to bear on an inner shoulder along the open end of a cylindrical casing and is adapted to support the two counters. In order to obtain a division as regular as possible of the scale for the indicator, the spiral spring is provided with several lugs on various points of its length and adjustable stops are provided for striking and stopping the several lugs one after the other on the speed to be measured increasing, whereby the active length of the spiral spring is step by step reduced and consequently the tension of the spring is in proportion increased.

Other improvements will be hereinafter set forth and pointed out in the claims.

I will now proceed to describe my invention with reference to the accompanying drawings, in which—

Figure 1 is a vertical central section through the speed-indicator in a preferred mode of execution on the line C—D in Fig. 2, Fig. 2 is a horizontal section through the same on the line A—B in Fig. 1, Fig. 3 is partly an elevation of the same and partly a section through the line E—F in Fig. 2, Fig. 4 is a horizontal section through the same on the line G—H in Fig. 1, Fig. 5 is a plan view of the single piece of sheet metal comprising a disk with radial arms and U-shaped radial ribs prior to their bending. Fig. 6 is a perspective view of the same piece of sheet metal, when bent, Fig. 7 is a view of the reciprocating slide, Fig. 8 is a perspective view of a wing of the fly prior to its attachment to the nave, Fig. 9 is a plan view of the spiral spring and of stationary stops, and Fig. 10 is a similar view of a modified spiral spring and of radial stops fastened on the shaft of the fly.

Similar characters of reference refer to similar parts throughout the several views.

The frame of the novel instrument consists of a cylindrical casing 1 and a circular plate 16. The casing 1 is open at the top and is closed with the plate 16, which is made to bear with its edge on a shoulder 30 of the casing. The bottom of the casing 1 is provided with a cylindrical projection 1^a, into which a cylinder 1^b is fitted, that may be secured in any known manner, for example by means of two pins or screws introduced into two opposite holes 1^c in the cylindrical projection 1^a. The cylinder 1^b has in the middle an inner annular projection 1^d forming two shoulders above and

below. Two outer race rings 1^a , 1^b are inserted in the cylinder 1^b from opposite sides and are made to bear respectively against the two shoulders of the projection 1^d . A shaft 3 carrying two inner race rings 3^a is mounted to turn on the two outer race rings 3^a by means of two parallel series of balls 2 , these parts forming two ball-bearings for the shaft 3 . The shaft 3 is to be driven in any known manner from any shaft, the speed of which is to be measured.

A cylindrical hollow drum 4 open at the top is rigidly connected with the upper end of the shaft 3 in any known manner, for example by means of a collar and by riveting as shown in Fig. 1. The lower ball-bearing is preferably protected from dust by means of a disk 3^b and a loose collar 3^c secured in any known manner. The drum 4 is closed with a cover 4^a , into the central opening of which a hollow worm 12 is fitted. Of course the cover 4^a and the worm 12 may be made in one, if so preferred.

The circular plate 16 is according to my invention a single piece of sheet metal so cut and bent as to form two pairs of parallel shields 17 , 17 and 18 , 18 , a lug 19 and a bridge 20 , which latter so much projects downward, that its middle is in proximity of the hollow worm 12 . Preferably the plate 16 is on its periphery provided with a notch 16^a (Fig. 2), in which a corresponding inner projection of the casing 1 engages, so as to prevent the plate from inadvertently turning.

In the left pair of shields 17 , 17 in Figs. 1 and 2 and also in the lug 19 the main shaft 26 of a counter is mounted to turn, which counter is described in the specification and illustrated in the drawing attached to my pending application for a U. S. patent filed on April 30, 1912 under Serial No. 694,288. Also a rod 43 is fastened in the two shields 17 , 17 and has loose on it a series of pinions 44 , 44 , which are adapted to severally mesh with the pins of the several numeral wheels 27 . The main shaft 26 carries on one end a long ratchet wheel 28 and is connected at the other end with a knob 45 , which can be pulled outward against the pressure of a helical spring 46 and then turned for "canceling" the counter in the manner described in the said application. In the right pair of shields 18 , 18 in Figs. 1 and 2 the main shaft $26'$ of a second counter is mounted to turn, which is similar to the first counter, excepting that the knob 45 for "canceling" the counter is omitted, so that the second counter counts continuously. I do not further describe the two counters, as their construction is immaterial to the present invention. A shaft 15 is mounted in the two shields 18 , 18 to turn and carries a worm wheel 13 , which meshes with the worm 12 .

already mentioned above. On one end the shaft 15 is provided with a crank disk $22'$ carrying a crank pin 22 . A reciprocating slide 24 (see Fig. 7) is provided for transmitting the motion of the shaft 15 to the two ratchet wheels 28 and $28'$ of the two counters in the following novel manner. The slide 24 is forked at both ends 25 , 25 and has a lug 23 , which is also forked. The two forked ends 25 , 25 of the slide 24 are made to compass the two main shafts 26 and $26'$, so that the slide can reciprocate, it being longitudinally guided by the two main shafts and prevented from lateral motion by the two shields 17 , 18 and the two ratchet wheels 28 , $28'$. The slot in the forked lug 23 is at right angles to the common axis of the slots in the two forked ends 25 , 25 . Into the slot of the lug 23 engages the already mentioned crank pin 22 , and it will be understood, that during the rotation of the shaft 15 the slide 24 will be reciprocated by the crank pin 22 . The slide 24 carries intermediate its ends two pins 46 , 46 in the plane of the two main shafts 26 , $26'$. On each pin 46 two oppositely disposed pawls 29 , 29 are mounted to rock, and are pressed together by means of a helical spring and are adapted to engage the ratchet wheel 28 or $28'$ from opposite sides. The upper pawl 29 is shorter than the lower one and is adapted to feed the ratchet wheel 28 , $28'$ one tooth forward during the motion of the slide 24 in one direction, while the lower pawl 29 feeds the ratchet wheel 28 , $28'$ one tooth forward during the motion of the slide in the opposite direction. As the two pairs of pawls 29 , 29 are disposed in opposite directions to one another (Fig. 3), of course the teeth of the two ratchet wheels 28 , $28'$ require to be oppositely placed.

Owing to the construction described of the plate 16 with the shields 17 , 18 , the lug 19 and the bridge 20 the mechanism above the hollow drum 4 occupies a comparatively small space, so that the drum can be made large, which is of special advantage.

The circular plate 16 is covered with a suitable dial 37 provided with two parallel slots or series of windows 38 , 38 , through which the figures on the numeral wheels 27 , 27 can appear one after the other. A springy ring 33 from sheet metal is fitted to the inside of the upper end of the casing 1 and is made to bear on the dial 37 . A suitable glass plate 32 is put on the edge of the casing 1 and on the ring 33 and is pressed by means of a ring 31 with the aid of a packing ring 39 , the ring 31 being tightly fitted or otherwise secured to the outside of the casing 1 , so that in this manner the plate 16 with the dial 37 is secured.

The upper end of the shaft 3 is bored to

form a step-box, wherein the step 7 of a small shaft 6 is made to turn. This shaft also turns in another bearing 8 provided in the top of the hollow worm 12, passes upward through a wide aperture 21 in the bridge 20 and also through a hole in the plate 16 and in the dial 37 and carries at the upper end a suitable indicator 40, for which a scale (not shown) is provided on the dial 37. The shaft 6 carries within the drum 4 a fly of the following construction: A disk 9 provided with eight radial slits and serving as a nave is fastened on the shaft 6 and is provided on the upper side with an annular groove 11 (Fig. 1). Eight radial wings 10 made from sheet metal and flanged at the inner ends, as shown at Fig. 8, are inserted with their inner ends in the radial slits of the disk 9, so that the two flanges of each wing 10 compass the nave 9 on both sides, after which the upper flanges of the wings 10 are pressed by means of a suitable stamp into the groove 11, whereby the wings 10 are rigidly connected with the nave 9. The fly so formed describes during the rotation of the drum 4 a body, which occupies only a part of the space of the drum. As the small shaft 6 of the fly 9, 10 is turnable on the one hand in a step-box provided in the upper end of the shaft 3 and on the other hand in the bearing 8 in the top of the worm 12, the fly 9, 10 is protected from the influence of any vibration of the casing 1. A spiral spring 14 is fastened with its inner end on the shaft 6 above the bridge 20 and is connected at its outer end with the bridge at 41, Fig. 10. The space of the drum 4 is to be filled with a suitable medium, in the present case with air, and it will be understood, that during the rotation of the drum 4 the spiral spring 14 would prevent the shaft 6 with the fly 9, 10 from turning relatively to the casing 1. In order to prevent this, the drum 4 is provided with four inner radial ribs 5. According to my invention these four ribs 5 are made from a piece of sheet metal cut in a shape clearly shown at Fig. 5 and provided with holes 5^a, 5^a, after which the four radial U-shaped arms are bent along the dotted lines shown in Fig. 5, so as to bend upward the four ribs 5, 5, as is illustrated at Fig. 6. The cross so formed is then inserted in the drum 4 and is there fastened on the bottom by means of rivets 5^b (Fig. 1) in the holes 5^a. Then the friction of the air produced by the passage of the wings 10 of the fly through the recesses 5^c, 5^c in the ribs 5 during the rotation of the drum 4 will tend to turn the fly through an angle, the amount of which corresponds to the resistance of the spiral spring 14. Trials have shown, that the division of the scale for the indicator 40 becomes under these circumstances irregu-

lar, the distance between any two division lines for the same difference in speed being greater for a larger speed than for a smaller speed. The reason for this irregularity resides in the fact, that the resistance offered by the friction of the air to the passage of the wings 10 of the fly through the recesses 5^c in the ribs 5 of the rotating drum 4 increases as the square of the speed or more, while the resistance of the spiral spring 14 to the torsion increases in the same proportion as the angle of torsion or in a similar proportion. In order to obviate this objection I provide the spiral spring 14 on various places with several lugs 34, for example three in Fig. 10, and fasten on the shaft 6 a small disk 36 with as many arms 35 as there are lugs and these arms serve as stops. When assuming the shaft 6 in Fig. 10 to turn in a direction opposite to that of the hands of a watch, whereby the spiral spring 14 is wound on and its tension is increased, then one of the arms 35 will strike the innermost lug 34, since it moves more rapidly around the axis than the lug, so that this arm in taking along with it the innermost lug 34 will practically shorten the active length of the spiral spring 14 by a piece extending from the small disk 36 to the said lug. The so shortened spiral spring will become less elastic than before and consequently its tension will increase so that it will offer a greater resistance to the turn of the fly. When the speed of the shaft 3 further increases, the next following arm 35 will strike and take along with it the middle lug 34, whereby of course practically the active length of the spiral spring 14 is further reduced and consequently its tension is further increased, so that its resistance against the turn of the fly is in proportion increased. When the speed of the shaft 3 still increases further, of course the third arm 35 will strike and take along with it the outer lug 34, whereby the active length of the spiral spring 14 is reduced to a minimum and its tension is increased to a maximum, so that owing to the more increased resistance of the spiral spring the shaft 6 and therewith the indicator 40 will move through a smaller angle than if the spiral spring 14 were left without lugs 34.

The arms 35, 35 are made from an elastic material, so that it is possible to bend them by hand in either direction and thus to regulate the resistance of the spiral spring, so that the division of the scale for the indicator 40 can in this manner be made uniform. Of course the arms 35, 35 are in spite of their elastic material sufficiently stiff, so as not to yield to the thrust of the lugs 34, 34. The described manner of regulating the tension of the spiral spring 14 may also be modified by rendering the arms 130

35, 35 stationary, as is shown at Fig. 9. Three arms 35', 35' (one being shown as straight and the two other as bent) made from a similar elastic material are fastened 5 on the bridge 20 at 41 and 42 and are made to engage in the path of the lugs 34', 34'. The spiral spring 14 is by way of example provided with two sets of three lugs 34', 34' each, of which one becomes operative for 10 the turn of the shaft 6 with the indicator 40 in one direction and the other set for the turn in the opposite direction. When assuming the shaft 6 with the indicator 40 to turn in the direction to the left (opposite 15 to that of the hands of a watch), while the speed to be measured increases, then first the upper straight arm 35' in Fig. 9 will strike and stop the outer lug 34' on the right, afterward the lower left bent arm 20 35' will stop the middle lug 34' and finally the lower right arm 35' will stop the inner lug 34', so that in this manner the active length of the spiral spring 14 is successively shortened and consequently 25 its resistance to the turn of the fly and the indicator relatively to the scale on the dial 37 is successively increased. By suitably bending the three arms 35', 35' by hand the resistance of the spiral spring 14 30 can be again regulated so as to render the division of the said scale uniform. When the shaft 3 is set to rotate in the opposite direction and its speed increases, of course the three arms 35', 35' will strike and stop 35 in the same order the lugs 34', 34' in the other set. In this manner the whole speed-indicator is rendered useful for measuring speeds of the rotation in both directions.

The speed-indicator described can be 40 varied in many respects without departing from the spirit of my invention.

I claim:

1. In a speed-indicator, the combination with a casing having a dial, of a driving 45 shaft mounted to turn in said casing at right angles to said dial, a closed hollow drum fastened at the inner end of said driving shaft and provided with inner radial ribs, a small shaft coaxial with said driving shaft mounted to turn in said hollow drum and extending through said dial, an indicator on said small shaft, a fly fastened on said small shaft in said hollow drum and adapted to pass between the radial ribs of 50 this drum, and a spiral spring connected at its inner end with said small shaft and at its outer end with said casing, said hollow drum being adapted to be filled with a medium and said spiral spring being adapted to counteract the friction of said fly in the medium.

2. In a speed-indicator, the combination with a casing having a dial, of a driving shaft mounted to turn in said casing at right angles to said dial, a hollow closed drum fas-

tened at the inner end of said driving shaft and provided with an inner shaft coaxial with said driving shaft mounted to turn in said hollow drum relatively thereto and extending through said dial, an indicator on said small shaft, a fly fastened on said small shaft in said hollow drum and adapted to pass between the ribs of this drum, a spiral spring connected at its inner end with said small shaft and at its outer end with said casing and provided with several lugs on various places, and adjustable means for stopping the several lugs of said spiral spring one after the other on the speed to be measured increasing, whereby the active length 70 of said spiral spring is successively shortened and consequently its tension is increased, said hollow drum being adapted to be filled with a medium and said spiral spring being adapted to counteract the friction of said fly in the medium.

3. In a speed-indicator of the class described, a fly consisting of a nave and several radial wings, the nave having radial slits for the wings and on one side an annular groove, and the wings being cut from sheet metal and flanged at the inner ends so as to compass the nave on both sides, while the flanges of the wings on one side are bent into the annular groove of the nave, where- 95 by the wings are secured.

4. In a speed-indicator of the class described, the combination with a closed hollow cylindrical drum, of a single piece of sheet metal cut and bent to form an annular central disk with radial arms and U-shaped wings at right angles to the arms, the central disk with the radial arms being fastened on the inside of the bottom of the drum and the U-shaped wings forming radial ribs along the bottom, the side wall and the cover of the drum.

5. In a speed-indicator of the class described, the combination with a frame, of a shaft turnable in said frame, means tending to turn said shaft in one direction, a spiral spring connected at the inner end with said shaft and at the outer end with said frame, lugs on various places of said spiral spring, and arms on said frame engaging in the path of said lugs and adapted to be bent by hand for adjusting the places where said lugs are to be stopped one after the other on the force turning said shaft increasing.

6. A speed indicator comprising a frame, 120 a shaft journaled therein, a closed hollow drum carried by the shaft, a spring-controlled spindle stepped into the shaft, vanes on the spindle that are rotatable within the drum, and a pointer operable by the spindle.

7. A speed indicator comprising a frame, a shaft journaled therein, a closed hollow drum carried by the shaft, a plurality of slotted arms fitted radially within the drum, a spring-controlled spindle stepped into the 130

shaft, vanes on the spindle adapted to rotate within the drum, and a pointer operable by the spindle.

8. A speed indicator comprising a frame, 5 a shaft journaled therein, a closed hollow drum carried by the shaft, a spindle stepped into the shaft, vanes on the spindle that are rotatable within the drum, a spiral spring

secured to the spindle, a plurality of lugs carried by the spring, stops adapted to be 10 engaged by the lugs, and a pointer operable by the spindle.
